UNITED STATES PATENT OFFICE.

FRANK G. McKLVEEN AND LESLIE W. NAYLOR, OF DENVER, COLORADO.

AUTOMOBILE-STARTER.

982,382.

Specification of Letters Patent. Patented Jan. 24, 1911.

Application filed April 16, 1910. Serial No. 555,964.

To all whom it may concern:

Be it known that we, FRANK G. McKLVEEN and LESLIE W. NAYLOR, citizens of the United States, residing in the city and county of Denver and State of Colorado, have invented certain new and useful Improvements in Automobile-Starters; and we do declare the following to be a full, clear, and exact description of the invention, such 10 as will enable others skilled in the art to which it appertains to make and use the same, reference being had to the accompanying drawings, and to the letters and figures of reference marked thereon, which form a 15 part of this specification.

Our invention relates to improvements in manually operated starters for automobiles, our object being to provide a simple device adapted to accomplish the starting function, 20 and which shall be easily operable and not liable to get out of repair.

In our improved construction we locate a manipulating device, as a hand or foot lever within convenient reach of the chauffeur or 25 person in charge of the machine, this lever being suitably connected with the engine shaft, whereby the necessary initial rotary movement may be imparted thereto.

A special feature of our starting mechanism consists in the employment of a segmental gear adapted to mesh with an adjacent pinion but normally disconnected therefrom. This gear segment is of such size, 30 with reference to its coöperating pinion, and has such relation to the other connections interposed between the segment and the engine shaft, that the latter may be rotated several times by a single operation of the 35 segment. Provision is made whereby, after the segment has been moved in the performance of the starting function, it is automatically returned to its normal position or out of engagement with its companion pinion. Furthermore, the direct connection 40 with the engine shaft includes a pawl-carrying sprocket-gear which acts upon a ratchet fast on the engine shaft. As soon as the engine is in motion, in the regular 45 performance of its function, the shaft, with its ratchet, rotates independently of the pawl-carrying gear, which ceases to move as soon as the actuating segment is disengaged from its coöperating pinion.

Having briefly outlined our improved construction, we will proceed to describe the same in detail, reference being made to the

accompanying drawing, in which is illustrated an embodiment thereof.

In this drawing: Figure 1 is a top plan view of an automobile equipped with our improved starting mechanism. Fig. 2 is a front elevation partly in section, looking in the direction of arrow 2, Fig. 1, showing the ratchet on the engine shaft and its co-operating pawl-carrying sprocket gear, 60 which is shown partly in section and on a larger scale. Fig. 3 is a section taken on the line 3—3, Fig. 2. Fig. 4 is a side elevation of the segmental gear member of the starting mechanism, together with its co-operating pinion and manipulating lever, the latter being shown partly broken away. In this view the parts are shown on a larger scale than in the other views, and the view is taken in the direction of arrow 4, Fig. 1. 70 Fig. 5 is a top plan view similar to Fig. 1, but partly broken away. In this view a foot lever is illustrated for manipulating the starter mechanism as distinguished from a hand lever which is disclosed in Figs. 1 and 4. Fig. 6 is a section taken on the line 6—6, Fig. 5, looking toward the right, the parts being shown on a larger scale. Fig. 7 is a view illustrating a modified form of 75 construction.

The same reference characters indicate the same parts in all the views.

Referring first to Figs. 1 to 4, inclusive, let the numeral 5 designate the running gear and body of an automobile upon which 80 is mounted an internal combustion engine 6 of any ordinary or suitable type. Journaled in bearings 7 and 8 mounted on the body or framework of the vehicle, is a rock-shaft 9 to one extremity of which is secured a hand lever 10, while its opposite extremity is equipped with a mutilated or segmental gear 12. Connected with the rock shaft is one extremity of a spiral spring 13 whose opposite extremity is attached to the framework of the vehicle, as shown at 14. The tension of this spring is so regulated that the rock shaft is normally held in such a position that the gear 12 is disengaged from a coöperating pinion 15. For this purpose the rock-shaft is equipped with an arm 16 with which the spring is connected, as shown at 17. The pinion 15 is fast on a shaft 18 journaled in suitable bearings 19. The shaft 18 extends at right angles to the rock shaft 9, the pinion 15 being mounted on the rear extremity of the said shaft. The forward ex- 100

tremity of the shaft is equipped with a sprocket wheel 20 which is connected by means of a chain 21 with a sprocket 22 loose on a sleeve or hub 23 secured to the engine shaft 24 by a locking pin or key 25. This sleeve 23 is so constructed that it may be readily applied to the engine shaft of any automobile, where the said shaft protrudes for cranking purposes. Upon the forward extremity of the sleeve 23 is screwed a ratchet ring 26, the teeth of which are engaged by pawls 27 carried by the sprocket wheel 22 and held in place thereon by bolts 28 passed through the sprocket wheel and through 10 a cap or casing 29 having an inwardly protruding flange 30 engaging the front face of the sprocket wheel. The said cap has an opening 31 which fits over the forward end of the sleeve 23 and engages a shoulder 32 formed thereon. This cap is secured in place by nuts 33 applied to the pawl-supporting bolts, and forms a sort of chamber within which the pawls 27 are located and concealed.

Assuming that the segmental gear 12 is in its normal position, or that shown in Figs. 1 and 4, if it is desired to start the machine, the hand lever 10 will be actuated to turn the rock shaft 9 in such a direction as to cause the teeth of the segmental gear to engage the pinion 15 of the shaft 18, whereby the said shaft may be caused to rotate a number of times, a corresponding movement being transmitted to the engine shaft through the medium of the sprocket gears 20 and 22, the chain 21 and the ratchet and pawl mechanism heretofore described. This movement of the engine shaft will be sufficient to start the engine. The chauffeur then releases the hand lever and the latter is returned automatically to its normal position resting upon a stop or bracket 34, the gear 12 being again disengaged from the pinion 15. As soon as the engine is started, its shaft 24, together with the sleeve 23 and the ratchet ring continues rotation, while the pawl-carrying sprocket 22 and the other mechanism connected therewith cease to move until again actuated for starting purposes.

Referring now to Figs. 5 and 6, in which the foot lever construction is illustrated, the rock shaft 9 is provided with an arm 35 connected by means of a spring 36 with a stationary part 37 of the machine, in a manner substantially the same as in the other form of construction, though the parts are slightly differently arranged. This rock shaft in this special form of construction, is equipped with a crank arm 38 connected by means of a link 39 with one extremity 40 of a foot lever 41 fulcrumed on the framework of the vehicle as shown at 42, its arm 43 above the fulcrum extending through the 60 floor 44 of the vehicle, its upper extremity

being equipped with a foot plate 45 arranged to be conveniently accessible to the chauffeur. It will thus be seen that in this form of construction the starting mechanism may be manipulated by the foot of the chauffeur in 70 the same manner as when operated by the hand lever.

While the mechanism, as heretofore described, is illustrated in connection with an engine whose shaft protrudes in front for cranking purposes, it is evident that it may be equally well applied to an engine having any other arrangement of shaft, as for instance a shaft protruding at the side. In Fig. 7 we have illustrated the mechanism as applied to a transversely arranged engine shaft protruding at one side of the vehicle. In this view it may be assumed that the engine shaft 24 protrudes at the right hand side of the vehicle where the lever 10 is located. In this event the rock-shaft 9 carrying the segmental gear 12 is operated in the same manner as heretofore described, and the segmental gear engages a pinion 47 fast on a shaft 48 carrying a sprocket-wheel 49 connected by means of a chain 50 with the sprocket 22 having bolts 28 carrying pawls 27 engaging the ratchet 26, all of which parts are substantially the same as illustrated in 80 Figs. 2 and 3.

Having thus described our invention, what we claim is:

1. In an engine starter for automobiles, the combination with an engine shaft, of a rock shaft, a segmental gear mounted thereon, an operating shaft extending parallel with the engine shaft, a pinion mounted on the operating shaft and coöperating with the segmental gear of the rock shaft, the segmental gear being normally disconnected from its coöperating pinion of the operating shaft, and an operative connection between the operating shaft and the engine shaft, including a sprocket wheel fast on the operating shaft, and a second sprocket wheel loosely mounted on the engine shaft and a chain connecting the two sprocket wheels, and a pawl and ratchet connection between the second named sprocket and the engine shaft, whereby the latter is initially actuated by the operation of the starting mechanism, after which the engine continues its rotation independently of the said sprocket, substantially as described.

2. In an engine starter for automobiles, the combination with an engine shaft, of a shaft extending parallel with the engine shaft, a pinion mounted on the said shaft, a segmental gear in operative relation with the said pinion, an operative connection between the shaft that extends parallel with the engine shaft and the engine shaft, including a sprocket wheel fast on the shaft extending parallel with the engine shaft, a second 130

5 sprocket wheel loosely mounted on the engine shaft, a pawl and ratchet connection between the latter sprocket wheel and the engine shaft, and a connection between the two sprocket wheels, and means for maintaining the segmental gear free from the pinion, substantially as described.

10 3. In an engine starter for automobiles, the combination with an engine shaft, of a rock shaft mounted on the vehicle, an operating shaft, a mutilated or segmental gear mounted on the rock shaft, a coöperating pinion mounted on the operating shaft, an operative connection between the operating shaft and the engine shaft, including a sprocket wheel fast on the operating shaft, and a second sprocket wheel loosely mounted on the engine shaft, a flexible connection between the sprocket wheels, a pawl and ratchet connection between the second named sprocket wheel and the engine shaft, and means for maintaining the segmental gear normally disconnected from its coöperating pinion of the operating shaft, substantially as described.

15 4. In an engine starter for automobiles, the combination with an engine shaft, of a rock shaft mounted on the vehicle, an operating shaft, an operative connection between the rock shaft and the operating shaft, a wheel fast on the operating shaft, a second wheel mounted on the engine shaft, a clutch connection between the engine shaft and the said wheel thereon, causing the wheel when rotated to turn the shaft and permitting the shaft when started to turn independently of the wheel, a suitable connection between the wheels of the operating and engine shafts, and means for normally

20 maintaining the rock shaft and the operating shaft in disconnected relation, substantially as described.

25 5. In an engine starter for automobiles, the combination with an engine shaft, of a rock shaft mounted on the vehicle, an operating shaft, an operative connection between the rock shaft and the operating shaft, means for normally maintaining the rock shaft and the operating shaft in disconnected relation, a wheel fast on the operating shaft, a second wheel mounted on the engine shaft, a ratchet and pawl connection between the engine shaft and the said wheel thereon, and a suitable connection between the wheels of the operating and engine shafts.

30 6. In an engine starter for automobiles, the combination with an engine shaft, of a rock shaft mounted on the vehicle, an operating shaft, an operative connection between the rock shaft and the operating shaft, means for normally maintaining the two shafts in disconnected relation, an operative connection between the operating shaft and the engine shaft, including a sprocket wheel fast on the operating shaft, a second sprocket wheel loosely mounted on the engine shaft, an operative connection between the two sprocket wheels, and a ratchet and pawl connection between the engine shaft and its sprocket wheel, substantially as described.

35 In testimony whereof we affix our signatures in presence of two witnesses.
